UNITED STATES PATENT OFFICE.

FRANKLIN G. PALMER, OF PHILADELPHIA, PENNSYLVANIA.

DESIGN FOR A LAMP.

SPECIFICATION forming part of Design No. 12,204, dated March 29, 1881.

Application filed November 4, 1879. Term of patent 7 years.

To all whom it may concern:

Be it known that I, FRANKLIN G. PALMER, of the city and county of Philadelphia, State of Pennsylvania, have invented a new and useful Design for Lamps, of which the following is a specification.

My invention has reference to designs for lamps having their wick-tubes located at a distance, laterally, from the oil-reservoir, and connected therewith by a supply-tube; and it consists in a design embodying, in a lamp of that class, an ornamental brace extending in a horizontal direction from the wick-tube to the oil-reservoir and substantially parallel with the supply-tube, and curved at its junction with the reservoir.

In the drawings are illustrated three modifications of my design, and in the same A is the oil-reservoir; B, the wick-tube; C, the supply-tube; D, the supporting tube or rod; E, the

brace, curved at F, and attached at e to the reservoir. The curve may be either upward and over, as shown in Figure 1, or upward and under, as shown in Fig. 2, or simply under, as in Fig. 3, the effect being in all three substantially the same. 25

What I claim is—

The design for lamp herein described, consisting of the reservoir A and wick-tube B, connected by the feed-tube C and brace E, the latter being curved, as at F, and substantially parallel to the supply-tube, as set forth. 30

In testimony that I claim the foregoing as my own I affix my signature in the presence of two witnesses.

FRANKLIN G. PALMER.

Witnesses:

JOHN T. ARMS,
CHARLES ZEPPOON.
